UNITED STATES PATENT OFFICE

2,002,386

DOUBLE PISTON FLUID MOTOR

Clyde E. Bannister, Akron, Ohio

Application May 15, 1931, Serial No. 537,617
Renewed November 17, 1933

10 Claims. (Cl. 121—119)

My present invention relates to fluid pressure motors, and more particularly to a novel and improved poppet valve motor.

The motor of my present application is particularly adaptable for use in conjunction with the deep well drilling apparatus illustrated and described in my prior and co-pending application, Ser. No. 271,923, filed April 21, 1928.

The advantages and desirability of a motor effecting an oscillating movement of the cutting bit, as the machine descends into the bore which it is forming, are fully set forth in said prior application, and reference thereto is hereby made.

An important object of the present invention is the provision of a poppet valve fluid pressure motor which may be freely suspended in a well bore and operate a cutting bit in an oscillating manner so as to feed itself constantly into the bore being formed.

Another object of the invention resides in the provision of a poppet valve motor which is simple and economical to build and assemble, and which is positive in operation.

Another object of the invention resides in providing means associated with a plurality of reciprocating pistons, to convert the reciprocations of said pistons into oscillations of the bit carrying shaft.

Another object of the invention resides in the provision of means, operable at a predetermined instant, to accelerate travel of said pistons in one direction.

Other objects and features of the invention reside in the particular construction and arrangement of the parts of my novel motor.

The above and other features and objects of the invention, details of construction, combinations of parts, and advantages, will be hereinafter more fully pointed out, described and claimed.

Referring to the drawings, illustrating a preferred embodiment of the present invention,

Fig. 1 is a side elevation of a well boring machine in which my novel motor is incorporated, in the process of drilling a well bore;

Fig. 2 is a longitudinal sectional view of my novel motor;

Fig. 3 is a longitudinal sectional view on the line 3—3 of Fig. 2;

Fig. 4 is a fragmentary longitudinal sectional view on the line 4—4 of Fig. 2;

Fig. 5 is a cross sectional view on the line 5—5 of Fig. 2;

Fig. 6 is a cross sectional view on the line 6—6 of Fig. 2;

Fig. 7 is a cross sectional view on the line 7—7 of Fig. 2; and

Fig. 8 is a cross sectional view on the line 8—8 of Fig. 2.

Referring now to the drawings, for a particular description of the invention, its construction and

operation, 1 designates a well bore, in which a working barrel comprised of a plurality of sections 2, 2 united by suitable joints 3 is suspended by means of flexible cables 4, these cables being controlled and operated by any usual or suitable surface equipment (not shown).

A flexible hose 5 is utilized to convey fluid under pressure from any usual or suitable pump (not shown) or other source of power above ground.

In Fig. 1 my novel motor is illustrated generally at 6, and as more clearly illustrated in Fig. 2, said motor comprises a cylinder block 7 and a sleeve 8, united in any desirable manner as by a locked threaded joint.

In the cylinder block 7 are formed two cylinders 9 and 10, in which are reciprocating pistons 11 and 12. Each piston 11 has depending therefrom a hollow piston rod 13 and 14 respectively, these piston rods being slidable and having a bearing in the bottom of the block 7.

Fixed to the block 7 at the top of the cylinder 9 is a plug 15 having an inlet port 16 therethrough, and fixed in the block 7 at the top of the cylinder 10 is a plug 17 having an inlet port 18 therethrough. Supported at its upper end in the cylinder block 7 and at its lower end in a plug 19 fixed in the lower end of the sleeve 8 is a shaft 20, this shaft 20 being provided with a collar 21 resting on an anti-friction bearing 22 in the plug 19.

A stuffing box 23 is provided surrounding the shaft 20 and fixed in the plug 19. The shaft 20 is provided with a plurality of spiral grooves 24, and formed on the lower end of each of the piston rods 13 and 14 is a lug 25 riding in said grooves. Also formed on the bottom or adjacent to the lower end of each piston rod 13 and 14 are lugs 26. These lugs 26 are adapted to ride in vertical slots 27 formed in a liner 28 which is held against rotation within the sleeve 8.

Slidable within the piston rod 13 is a valve stem 29 having a valve 30 on its upper end, said valve 30 being adapted to seat, at predetermined intervals, on the plug 15 to seal the inlet port 16. A stop 31 is fixed to the barrel section 2 by rivets 32 or in any other desired manner. The lower end of the valve stem 29 is provided with a cap or button 33, and surrounding the valve stem 29 and resting against said cap 33 is a flanged sleeve 34. A flanged sleeve 35 also surrounds the stem 29 and is slidable thereon and abuts against the lower end of the piston rod 13. Surrounding the valve stem 29 and confined between the flanges of the sleeves 34 and 35 is a coiled spring 36.

The cap 33 is in constant engagement with the upper surface of an annular rocker 37, at one side of the pivot points 38, these pivots comprising screws projecting through the liner 28 and engaging the bearing journals 39 of the rocker 37. In engagement with the upper surface of the

rocker 37, at the opposite side thereof, is a cap 40 on the lower end of a valve stem 41, said valve stem being provided with sleeves 42 and 43 and a coiled spring 44, similar to the sleeves 34 and 5 35 and coiled spring 36. At the upper end of the valve stem 41 is a valve 45, a stop 46 being provided to limit upward movement of the valve 45, similar to the stop 31.

Fixed to the valve stem 29, and movable therewith, is a sleeve valve 47, a pin 48 securing said sleeve valve to the stem 29.

Exhaust ports 49 communicate with the upper end of the cylinder 9 and with vertical fluid conducting passages 50, and exhaust ports 51 communicate with the cylinder 10 and with said vertical passages 50. A sleeve valve 52 is fixed to the valve stem 41 by a pin 53, the location of this valve 52 on its stem 41 being similar to the location of the valve 47 on the stem 29.

20 The lower end of the shaft 20 carries a bit 54 provided with the cutting edges 55.

25 The vertical fluid conducting passages 50 meet at their lower ends, as at 56, and communicate with the hollow interior 57 of the shaft 20, the central bore of the shaft 20 extending completely therethrough and through the bit 54, fluid conducted through said passage being utilized to cool the bit as well as flush the cuttings out of the bore being formed.

30 A series of channels 58 is provided through the lower end of the block 7 communicating with the cylinder 9 beneath the piston 11 and with the hollow interior 59 of the sleeve 8. A series of channels 60 likewise communicates with the cylinder 10 beneath the piston 12 and with the hollow interior 59 of the sleeve 8. A supply of lubricant sufficient to occupy the space from the bottom of the piston 11 through the cylinder 9, channels 58, interior 59, channels 60 and cylinder 40 10 beneath the piston 12 is provided. Thus all moving parts from the pistons downwardly, are continually bathed in oil, insuring long life to the moving parts and hence to the motor.

45 The operation of my present novel motor is simple, and will be readily understood by those skilled in this art, being briefly described as follows:

Fluid under pressure being conveyed through the hose 5, and through the hollow interior 61, 50 of the barrel sections 2, will enter the inlet port 16, when the motor is in the position illustrated in Fig. 2. The sleeve 47 closes the outlet ports 49, so that the fluid under pressure will bear against the top of the piston 11, forcing the same downwardly in its cylinder 9, and compressing the spring 36 between the flanges of the sleeves 35 and 34.

55 This downward movement of the piston 11, with its associated lug 25 riding in one of the grooves 24, will effect a rotative movement of the shaft 20, and the lug 25 associated with the piston 12, riding in the other groove 24, will cause the piston 12 to rise, the vertical movement of the piston 12 being assisted by the spring 44. As the pistons 11 and 12 and their rods 13 and 14 are thus reciprocated, the lugs 25 riding in the spiral grooves 24 will effect an oscillatory movement of the shaft 20, this movement in turn being transmitted to the bit 54. As the sleeve 35 is moved downwardly by the piston rod 13, it will compress the spring 36 until said sleeve comes in contact with the upper end of the sleeve 34, forcing said sleeve, and hence the valve stem 29 downwardly against the rocker 37. During 75 this movement of the sleeve 35, the closed valve 45

is maintained on its seat by the fluid pressure in the barrel 2 bearing against its upper surface. By the time the sleeve 35 engages the sleeve 34, the spring 36 will have been compressed past its central position.

5 By this time the piston 12 will have risen substantially to the top of the cylinder 10, and as the rocker 37, through the positive action above described, is rocked on its pivots, the valve 45 will be unseated and the contracted spring 36 10 will shoot the valve stem 29 downwardly, seating the valve 30 over the inlet port 16, preventing the further admission of fluid therethrough, and simultaneously moving the sleeve valve 47 downwardly to open or expose its associated exhaust ports. As the valve stem 29 is forced downwardly, the rocker 37 will be pivoted on its pivots 38, as above explained, raising the valve stem 41 and valve 45, with a snap action due to the compression of the spring 36, and opening the inlet port 18 to the admission of fluid under pressure, whereupon the cycle just described will be repeated, effecting an oscillatory movement of the shaft 20 in the opposite direction, and hence an opposite oscillation of the bit 54. It will be noted that the area of the top of the piston 11 is greater than the area of the top of the valve 45, so that when the piston 11 has descended to the point where the sleeve 35 has engaged the sleeve 34, the pressure on the piston 11, coupled with the compression of the spring 36, will be sufficient to overcome the pressure on the valve 45, breaking the contact between said valve and its seat, whereupon the expansion of the spring 36 will complete the raising of said valve 45.

35 As the piston 12 is rising, and before the valve 45 is opened, fluid in the cylinder 10 will be forced therfrom through the discharge ports 51, whence said fluid will traverse the passages 50 and be forced through the port 57 of the shaft 20 and downwardly through the bit 54 into the bottom of the bore being formed.

40 As the valve stem 29 is snapped downwardly, carrying with it the sleeve valve 47 and thus opening the exhaust ports 49, the valve stem 41, 45 being raised by the rocker 37 will carry the sleeve valve 52 upwardly, and close the exhaust ports 51.

45 The operation of my novel motor will continue so long as fluid under pressure is conveyed 50 thereto.

55 The upper ends of the passages 50 are closed by plugs 62, as clearly illustrated in Figs. 2 and 3.

The barrel 2, coupled with the block 7, sleeve 8, plug 9, liner 28, and other non-oscillating parts, 55 are of such a mass and weight as to preclude any possibility of the oscillations of the shaft 20 and bit 54 being transmitted thereto. Thus I am enabled to utilize the free suspension illustrated, that is, the cables 4.

60 As described in my said prior application, this free suspension, coupled with an oscillating cutting bit and motor therefor permits the formation of a vertical bore, a highly desirable and important result which is incapable of achievement 65 with any prior well drilling device or apparatus of which I am aware.

I believe that the fluid pressure motor illustrated and described herein is novel, and I have therefore claimed the same broadly in the present application.

70 While I have necessarily described my present invention somewhat in detail, it will be appreciated that I may vary the size, shape and arrangement of parts within reasonably wide limits, 75

without departing from the spirit of the invention.

My invention is further described and defined in the form of claims as follows:

5 1. In a fluid pressure motor, a pair of cylinders, a piston reciprocable in each of said cylinders, a hollow rod depending from each of said pistons, an inlet port at the upper end of each of said cylinders, a valve cooperating with each inlet port, a valve stem depending from each valve and extending through its respective piston and piston rod, a rocker, the lower end of each of said valve stems being in engagement with said rocker, and means to pivot said rocker to seat one valve and unseat the opposite valve.

10 2. In a fluid pressure motor, a pair of cylinders, a piston reciprocable in each of said cylinders, a hollow rod depending from each of said pistons, an inlet port at the upper end of each of said cylinders, a valve cooperating with each inlet port, a valve stem depending from each valve and extending through its respective piston and piston rod, a rocker, the lower end of each of said valve stems being in engagement with said rocker, and means to pivot said rocker to seat one valve and unseat the opposite valve, and resilient means to accelerate the movement of said valves.

15 3. In a fluid pressure motor, a pair of cylinders, a piston reciprocable in each of said cylinders, a hollow rod depending from each of said pistons, an inlet port at the upper end of each of said cylinders, a valve cooperating with each inlet port, a valve stem depending from each valve and extending through its respective piston and piston rod, a rocker, the lower end of each of said valve stems being in engagement with said rocker, means to pivot said rocker to seat one valve and unseat the opposite valve, and means to limit the movement of said valves.

20 4. In a fluid pressure motor, a pair of cylinders, a piston reciprocable in each of said cylinders, a hollow rod depending from each of said pistons, an inlet port at the upper end of each of said cylinders, a valve cooperating with each inlet port, a valve stem depending from each valve and extending through its respective piston and piston rod, a rocker, the lower end of each of said valve stems being in engagement with said rocker, means to pivot said rocker to seat one valve and unseat the opposite valve, resilient means to accelerate the movement of said valves, and means to limit the movement of said valves.

25 5. In a fluid pressure motor, a pair of cylinders, a piston reciprocable in each of said cylinders, a hollow rod depending from each of said pistons, an inlet port at the upper end of each of said cylinders, a valve cooperating with each inlet port, a valve stem depending from each valve and extending through its respective piston and piston rod, a rocker, the lower end of each of said valve stems being in engagement with said rocker, means to pivot said rocker to seat one valve and unseat the opposite valve, and resilient means associated with each valve stem and alternately operable to accelerate the movement of said valves.

30 6. In a fluid pressure motor, a pair of cylinders, a piston reciprocable in each of said cylinders, a hollow rod depending from each of said pistons, an inlet port at the upper end of each of said cylinders, a valve cooperating with each inlet port, a valve stem depending from each valve

and extending through its respective piston and piston rod, a rocker, the lower end of each of said valve stems being in engagement with said rocker, positive means to initiate movement of said rocker, and resilient means to accelerate movement of said rocker to seat one valve and unseat the opposite valve.

35 7. In a fluid pressure motor, a pair of cylinders, a piston reciprocable in each of said cylinders, a hollow rod depending from each of said pistons, an inlet port at the upper end of each of said cylinders, a valve cooperating with each inlet port, a valve stem depending from each valve and extending through its respective piston and piston rod, a rocker, the lower end of each of said valve stems being in engagement with said rocker, positive means associated with each valve stem to initiate movement of said rocker, and resilient means associated with each valve stem and alternately operable to accelerate movement of said rocker to seat one valve and unseat the opposite valve.

40 8. In a fluid pressure motor, a pair of cylinders, a piston reciprocable in each of said cylinders, a hollow rod depending from each of said pistons, an inlet port at the upper end of each of said cylinders, a valve cooperating with each inlet port, a valve stem depending from each valve and extending through its respective piston and piston rod, a rocker, the lower end of each of said valve stems being in engagement with said rocker, and means to pivot said rocker to seat one valve and unseat the opposite valve, exhaust ports adjacent to the upper end of each cylinder, a sleeve valve fixed to each of said valve stems and operable thereby to close the exhaust ports of a cylinder when the inlet port to said cylinder is open.

45 9. In a fluid pressure motor, a pair of cylinders, a piston reciprocable in each of said cylinders, a hollow rod depending from each of said pistons, an inlet port at the upper end of each of said cylinders, a valve cooperating with each inlet port, a valve stem depending from each valve and extending through its respective piston and piston rod, positive means associated with each valve stem to initiate movement of the opposite valve, and resilient means associated with each valve stem and operable to accelerate movement of said positive means to unseat said opposite valve.

50 10. A fluid pressure motor comprising a shaft formed with at least two cam surfaces of opposite pitch, at least two alternating piston structures coaxing with said cam surfaces to drive the shaft, a casing in which the shaft is rotatively mounted, the casing having a pressure fluid chamber for each of the said piston structures, poppet valve seats in adjacent end walls of the chambers, slide valve ports in the side walls of the chambers adjacent the poppet valve seats, a valve stem for each chamber slidably extending through the piston thereof, a poppet valve and a slide valve secured on each of the said valve stems, a lever mechanism compelling the valve stems to reciprocate oppositely, contact means on each piston structure and its valve stem for actuating the other valve stem, and yielding means interposed operatively between each piston structure and its valve stem for impelling the other valve stem beyond its movement compelled by the contact means.

CLYDE E. BANNISTER.
